UNITED STATES PATENT OFFICE

2,457,990

IRONING MACHINE CONTROL

Donald K. Ferris, Dayton, Ohio, assignor to General Motors Corporation, Dayton, Ohio, a corporation of Delaware

Application November 14, 1942, Serial No. 465,563

3 Claims. (CL 38—56)

1

This invention relates to domestic appliance and more particularly to ironing machines.

An object of this invention is to provide a construction in an ironing machine or machines of similar character, so that it may be easily moved around over the supporting floor and thereafter locked in position while operating said machine.

Further objects and advantages of the present invention will be apparent from the following description, reference being had to the accompanying drawings, wherein a preferred form of the present invention is clearly shown.

In the drawings:

Fig. 1 is a view in perspective, and somewhat diagrammatic, showing a machine embodying my invention;

Fig. 2 is a plan view, partly in cross-section, and with parts broken away, showing a pedal construction;

Fig. 3 is a vertical cross-sectional view, taken along the line 3—3 of Fig. 2; and

Fig. 4 is a view similar to Fig. 3, but showing the parts in a different position.

An ironer embodying this invention may be provided with a supporting frame 10, which carries a mechanism, such as an ironing roller 11, an ironing shoe 12, and mechanism 13 for rotating the roller 11 and bringing the shoe 12 into contact with the roller 11. The mechanism 13 may be, internally, the same as disclosed in my Patent Number 2,363,518, granted November 28, 1944. The frame 10 may be provided with downwardly directed supports 14 at its ends, and these supports 14 may in turn be supported by a plurality of casters 15. Preferably there are four of such casters.

A manipulator or pedal 16 is provided for controlling the operation of the mechanism carried by the frame. The pedal 16 is connected by the rod 17 with the mechanism 13. The pedal is movably supported on the frame 10 by end levers 18 at each end of the pedal 16, these levers being fulcrumed at 19. The levers 18 are covered and are connected by a curved sheet metal cap 18a to form the long pedal 16. Upon downward movement of the pedal 16, the ironing mechanism is caused to operate.

Preferably the pedal 16 is movable to a plurality of positions to provide for different types of operation of the mechanism. For example, downward movement to a first position of the pedal 16 causes the roll 11 to rotate at one speed, and the shoe 12 to move into engagement with the roll 11. At a second position of the pedal 16, the roll 11 may be caused to rotate at a different speed.

2

At a third position of the pedal 16 the shoe 12 may be brought into engagement with the roll 11, but the roll 11 may be maintained stationary. At a fourth position of the pedal, the brake means hereinafter to be more fully described may be applied to prevent movement of the ironer over the supporting floor. The features of causing the various operations of the roll 11 and shoe 12 form no part of this invention and are more fully described in my copending application S. N. 367,989, filed November 30, 1940, Patent No. 2,363,518, patented November 28, 1944, wherein they are claimed.

Brake means are provided to station the ironer on the supporting floor at a selected place. Preferably this brake means is of a construction such that upon movement of the pedal 16 to its lowermost position, such brake means is applied, while movement of a second pedal 20 automatically releases the brake means and again permits movement of the ironer about the supporting floor on the casters 15. This brake means may take the form of a member or rod 21 which is movable downwardly into engagement with the supporting floor. The rod 21 may be provided with a rubber knob 22 at the end, to come into frictional engagement with the floor. If desired, a plurality of such rods 21 may be provided, such as one near each end of the pedal 16.

30 The rods 21 may pass through openings 23 and 24 in channel-irons 25a and 25, which extend between the two end supports 14, underneath the pedal 16. The rod 21 is ordinarily urged upwardly by the spring 26, which reacts on the top of member 25 and on the washer 27 at the end of the rod 21. When the pedal 16 is moved downwardly, it comes into contact with the top of the rod 21, in its lowermost position, and moves the rod 21 into engagement with the floor.

40 A device is provided for automatically locking the rod 21 when it is moved downwardly, and also for releasing the rod 21 when it is desired to move the ironer about the floor. For this purpose, each rod 21 is controlled by an angularly shaped pedal 20, which extends through a slot 28 in the cap 18a. The construction is such that when the rod 21 is moved downwardly the edges 29 and 30 of an opening in the pedal bite into the rod 21 and lock it in its lowered position.

45 For this purpose, the lower end 20a of the pedal 20 is inserted in an opening 31 in the member 25. A spring 32 is coiled about the rod 21 and expands against the top of channel member 25a and the bottom of the pedal 20. The reaction of the spring 32 causes the pedal 20 to move upwardly

in biting position and remain there until it is pushed down by the user's foot.

The operation of the device is such that the ironer may be moved about the floor on its casters 15. When it is desired to station the ironer at a selected place, the user may push the pedal 16 quickly downward to its lowermost position. This causes the rods 21 to move downwardly with their knobs 22 engaging the floor. The rods 21 are locked in their downward position by the biting action of the pedals 20. Thereafter the ironer may be used, under the control of pedal 16, for any ironing operations desired. When it is desired to move the ironer to some other place on the floor, the user pushes down the pedals 20, at each end of the pedal 16, and this releases the rods 21, so that they may fly upward under the power of springs 26, thus disengaging them from the floor, and allowing the ironer to be moved about the floor.

While the form of embodiment of the invention as herein disclosed, constitutes a preferred form, it is to be understood that other forms might be adopted, all coming within the scope of the claims which follow.

What is claimed is as follows:

1. An ironing machine comprising an elongated standard having downwardly directed supports at each end of said standard, ironing mechanism supported on said standard, a pedal extending between said supports and controlling the starting of the ironing operation of said mechanism by downward movement of said pedal to ironing controlling position, casters on said supports, and brake means for preventing movement of said ironing machine on said casters, and means rendered operative by downward movement of said pedal beyond its ironing controlling positions for applying said brake means.

2. An ironing machine comprising an elongated standard having downwardly directed supports at each end of said standard, ironing mechanism supported on said standard, a pedal extending

between said supports and controlling the starting of the ironing operation of said mechanism by downward movement of said pedal to ironing controlling position, casters on said supports, brake means for preventing movement of said ironing machine on said casters, means rendered operative by downward movement of said pedal beyond its ironing controlling position for said ironing mechanism, and release means for said brake means.

3. An ironing machine comprising a standard having downwardly directed supports, an ironing roller, an ironing shoe and driving mechanism for rotating said roller and for providing engaging movement between said roller and shoe supported on said standard, casters on said supports, a pedal extending between said supports and controlling the starting of said mechanism, brake means for preventing movement of said ironing machine on said casters, means rendered effective by operation of said pedal for applying said brake means, and release means for said last named means.

DONALD K. FERRIS.
